[57] CLAIM

The ornamental design for the trailer security hitch, as shown and described.

DESCRIPTION

FIG. 1 is a perspective view of the trailer security hitch; FIG. 2 is a side elevational view of the design; FIG. 3 is a side elevational view of the design of FIG. 1 taken from the opposite side of that shown in FIG. 2; FIG. 4 is a front elevational view of the design; FIG. 5 is a rear elevational view of the design; FIG. 6 is a top elevational view of the design; FIG. 7 is a bottom view of the design; and,

FIG. 8 is a perspective view of the trailer security hitch, and illustrating in phantom the manner in which the trailer security hitch may be mounted on a tree or the like. The broken line showing of environment is for illustrative purposes only and forms no part of the claimed design.
